UNITED STATES PATENT OFFICE.

MARTIN L. WYMAN, OF BOSTON, MASSACHUSETTS, ASSIGNOR TO HIMSELF AND CHARLES E. MOORE, OF SAME PLACE.

IMPROVEMENT IN ELEVATORS.

Specification forming part of Letters Patent No. 152,718, dated June 30, 1874; application filed February 7, 1874.

To all whom it may concern:

Be it known that I, MARTIN L. WYMAN, of Boston, in the county of Suffolk and State of Massachusetts, have invented an Improvement in Elevators; and I do hereby declare that the following, taken in connection with the drawings which accompany and form part of this specification, is a description of my invention sufficient to enable those skilled in the art to practice it.

The invention has reference to a novel construction of a fluid-retarder mechanism to be used in connection with hotel and warehouse elevators, to regulate the descent of the car.

In my invention I place at one end of the drum-shaft a liquid-containing chamber, the drum-shaft passing through the wall of the chamber, and having upon its end within the chamber a gear that meshes into and drives a gear journaled in the chamber-walls. Extending around, or partially around, the second gear is a partition, separating the gear-chamber from another chamber or channel communicating, at each end, with the main chamber, but having at one end a valve, which, resting upon its seat, covers the channel, and, when raised from its seat, leaves a free passage between the channel and chamber, said valve having a small orifice extending through it, so that when closed there is a restricted passage between the channel and chamber.

In the rotation of the drum and drum-gear, as the car is raised the two gears are so rotated as to impel the liquid through the channel from the open end toward the valve-controlled end thereof, the pressure of the water opening the valve, and the liquid circulating freely from chamber to channel, and channel to chamber. The weight of the valve holds it normally upon its seat, to cover the channel-mouth; and, as the drum and gear rotate in the opposite direction as the car descends, the rotation of the gears forces the liquid against the closed valve, and, as the liquid can only enter the channel through the valve-orifice, the resistance offered by the liquid to the rotation of the gears insures the slow descent of the car, or its descent as fast, and only as fast, as the liquid can pass through the valve-aperture into the channel.

The invention consists in the combination, with the hoisting-drum, of a retarding mechanism, acting as thus generally described.

The drawing represents an elevator and a retarding mechanism embodying my invention.

Figure 1 shows the elevator in plan. Fig. 2 is a side elevation, the cap-plate of the retarder mechanism being removed. Fig. 3 is an enlarged elevation, showing the open valve. Fig. 4 is a similar elevation, showing the closed valve.

a denotes the hoisting-drum, having its shaft journaled in suitable bearings. *b* is the car; *c*, the hoisting-rope. Upon the end of the shaft *d* is fixed a gear, *e*, meshing into a gear, *f*, the journals of which gear *f* are supported in suitable bearings in the side walls *g* of a case, *h*. The two gears are contained within the chamber *i* of this case, the gears occupying the main part of the chamber, and there being, in the lower part of the chamber, a channel, *k*, separated from the gear *f* by a partition, *l*, which partition is concentric with, and close to, the teeth of said gear, as seen in Figs. 2 and 3. The channel opens into the main chamber at one end, as seen at *m*, and its opposite end opens into the chamber, except as controlled by a valve, *n*, one end of the partition *l*, and a shoulder, *o*, forming the seat of this valve, the valve normally covering the channel-opening *p*, as seen in Fig. 2. This valve has an orifice, *q*, extending through it, so that, when closed, there is still a passage from the chamber to the channel-mouth *p*, such passage being through this restricted opening *q*.

The chamber *i* is filled with oil or other suitable liquid, and when the car is ascending the gears rotate, as denoted by the arrows in Fig. 2, and by their action force the liquid through the channel *k* in the direction of the arrow seen in Fig. 3, the pressure of the liquid opening the valve, and the liquid circulating freely through the channel and chamber, from chamber to channel and channel to chamber. But, when the drum rotates in the opposite direction, as the car descends, the gears rotate in the direction of the arrows seen in Fig. 2, and the valve, closed by gravity, obstructs the free passage of the liquid into the channel, the liquid having to pass into the channel through the ori-

fice *q*, and the pent-up liquid forming such impediment to the free flow of the liquid into the channel as to insure the regular descent of the car, and prevent, under any and all circumstances, an over-rapid descent of the car. In these operations the teeth of the gears are the impelling agents to create the flow of the liquid, their meshing-surfaces forming, at all times, a wall against the passage of the water in a direction opposite to their path of rotation.

The chamber and channel may be formed otherwise than in the specific arrangement shown; but the construction represented is simple and efficient.

I claim—

The gear and liquid containing chamber *i*, channel *k*, valve *n*, and its orifice *q*, and the gears *e f*, in combination with the hoisting-drum, and forming a retarder, substantially as described.

Executed this 22d day of December, A. D. 1873.

MARTIN L. WYMAN.
